WARP DYE BEAM

Filed July 16, 1945

UNITED STATES PATENT OFFICE

2,548,899

WARP DYE BEAM

Homer V. Lang, Charlotte, N. C.

Application July 16, 1945, Serial No. 605,253

2 Claims. (Cl. 68—198)

1

This invention relates to a warp dyeing beam head and more especially to a warp dyeing beam head having the improvement of the circular flange on the head over which the perforated cylinder fits projecting further toward another warp beam head at the opposite end of the perforated cylinder thus giving a greater strength to the connection between the perforated cylinder and the warp beam head.

Dyeing beams are usually made with heads from twenty-eight to thirty-two inches in diameter, and the perforated cylinders usually run from eight inches in diameter to twenty-four inches in diameter. All of them are approximately fifty-four and three-eighths inches between the heads. These beams are for dyeing warps, and there is usually disposed on one of these beams about four hundred pounds of yarn. This yarn is wound onto the beams on a warper, the perforated beam cylinder riding down on the drum of the warper at the beginning of the winding operation. This drum on which the perforated cylinder rests is five-eighths to three-fourths of an inch shorter than the inside length of the beam. By riding on the cylinder the warper drum drives the beam and also gives it a braking surface for stopping the cylinder if an end breaks down. By driving the beam from the warper drum, the heads are hanging down supported only by the ends of the perforated beam cylinder.

These perforated cylinders have their perforations usually seven-sixteenths of an inch in diameter on five-eighths of an inch staggered centers, but sometimes these perforations vary in size as well as in the manner of disposition. Perforations have to be all the way to the end of the cylinder in order for the yarn to dye right in the corner where the cylinder joins the beam head.

Heretofore it has been common practice to make a shoulder about one half inch high, that is an annular shoulder around the inside surface of the beam head, and to assemble the cylinder over these annular projections or shoulders and then suitable bolts or tie rods are passed through the beam heads and in the space inside of the perforated cylinder to thus hold the heads and the cylinder in assembled relation. The perforated cylinders are usually made from stainless steel or some other non-corrosive material and are usually about one-eighth of an inch thick. In the severe service to which these beams are subjected, running at about five hundred revolutions per minute on high

2

speed warpers, and then suddenly stopping when an end breaks down, the head being supported by the cylinder, there is a tendency to stretch the cylinder in the ends so that the heads become loose.

It is an object of this invention to provide a warp dyeing means having a perforated cylinder and head members with the head members having annular shoulders projecting towards each other and over which the ends of the perforated cylinder fit, the annular shoulders not only being grooved peripherally but also being grooved longitudinally and also having gaps cut therein whereby the dyeing fluid can pass through the perforations and grooves in these annular shoulders and out through the perforations.

It is another object of this invention to provide a warp dyeing beam comprising a pair of head members each of which has an annular shoulder on the inside surface thereof over which a perforated cylinder is adapted to be fitted, the shoulders extending further inwardly than has heretofore been the case to provide greater support for the ends of the perforated cylinder and said annular shoulders having gaps cut therein and also having a peripheral groove extending therearound on the exterior of the annular shoulders and also having holes extending through the shoulder members and said shoulder members on their exterior surface having longitudinally extending grooves so that dyeing or bleaching fluid can pass through the gaps cut in the shoulders and through the holes of the shoulders and through the longitudinally extending grooves in the shoulders and circulating laterally around the exterior of the shoulders and out through the perforations in that portion of the cylinder which is fitting over the shoulders projecting from the beam head.

Some of the objects of the invention having been stated, other objects will appear as the description proceeds when taken in connection with the accompanying drawings in which:

Figure 1 is an elevation of a warp dyeing beam head showing the left hand end thereof in section;

Figure 2 is a view on an enlarged scale looking along the line 2—2 in Figure 1 and showing portions of the head broken away and also omitting the perforated cylinder which is normally disposed therearound;

Figure 3 is an elevation of the right hand end of the warp dye beam in Figure 1 and showing the cylinder in section and portions of the head broken away.

Referring more specifically to the drawings, the

numerals 9 and 10 indicate the heads of a warp dye beam and these heads have a conventional central opening 11 in each of the same and they are held together by means of a number of bolts 12 passing through the beam heads. The beam heads are usually lined on their inner or proximate surfaces where they are engaged by the yarn by any non-corrosive material such as lead and indicated by reference character 13. These beam heads instead of having about one half inch annular rib projecting from the inner surface thereof and concentric with the center hole 11, have an annular rib of about two or two and a half inches projecting therefrom, this rib being indicated by reference character 14. There is one on each of the heads 9 and 10 and a perforated cylinder 15 is adapted to fit over these annular ribs 14 and against the beam heads 9 and 10. It is to be noted that the lead lining 13 of the inner surface of the beam heads instead of being disposed all the way in to where the rib 14 projects outwardly, stops short of this point so that the ends of the cylinder fit against the solid steel of the beam heads instead of against the lead which might give way and cause the connection between the cylinder 15 and the heads 9 and 10 to become loosened. These annular ribs 14 have suitable gaps 16 cut therein and also have suitable holes 17 passing therethrough. The ribs 14 also have a peripheral groove 18 passing entirely around the exterior surface thereof and there are also longitudinally extending grooves 19 on the exterior of the ribs 14, these longitudinally extending grooves are bisected by the peripheral groove 18.

By having the annular ribs 14 much longer than on warp beams heretofore used, the weight of the warp beam resting on the warper drum is supported by these annular ribs 14 instead of having to be supported by the cylinder 15 which often gives way under this great load. It is also seen that the ribs 14 can project inwardly towards each other any desired length as the dyeing fluid, for example, when it is forced to the inside of the perforated case 15 will pass out through the gaps 16 and through the holes 17 and also flow out along the longitudinal grooves 19 and then from all of these perforations and grooves the dye can flow along peripheral groove 18 and out along the perforation in that portion of the cylinder 15 which is disposed over the ribs 14. Regardless of whether the fluid is flowing outwardly through the perforated cylinder or is reversed and flows inwardly through the yarn and through the perforated cylinder, the same is true in that the dyeing fluid or bleaching fluid whichever is used can have unimpeded flow through the perforated cylinder and through the openings in the rib 14 and through the grooves in rib 14 and thus the extreme corner portion of the yarn at the junction point between the heads 9 and 10 and the

perforated cylinder 15 will be dyed or bleached just as well as the other yarn on the other portions of the cylinder.

In the drawings and specification there has been set forth a preferred embodiment of the invention, and although specific terms are employed, they are used in a generic and descriptive sense only, and not for purposes of limitation, the scope of the invention being defined in the claims.

I claim:

1. A warp dyeing beam comprising a pair of head members and a cylinder having spaced perforations throughout its length, the head members each having an annular projection disposed on the proximate surfaces thereof and over which the ends of the perforated cylinder are adapted to fit, the annular projections having perforations therethrough through which the fluid in dyeing and bleaching may pass, the exterior of the annular projections having a peripheral groove therein and also having longitudinally extending grooves bisected by the peripheral groove, and means penetrating the head members and disposed on the interior of the cylinder for securing the heads against the ends of the cylinder.

2. A warp dye beam member comprising a perforated cylinder and a pair of head members, the head members having annular ribs projecting from the proximate surfaces thereof, the ribs having perforations therethrough and having a circumferential groove on their exterior surface over which the ends of the perforated cylinder fit, whereby a treating fluid may pass in either direction through the ribs and between the ribs and the perforated cylinder and through the perforations in the cylinder, and means penetrating the head members and disposed on the interior of the cylinder for securing the heads against the ends of the cylinder.
